C. C. MEURISSE

POLO MALLETS

Filed Aug. 21. 1922

UNITED STATES PATENT OFFICE.

CHARLES C. MEURISSE, OF CHICAGO, ILLINOIS.

POLO MALLET.

Application filed August 21, 1922. Serial No. 583,071.

To all whom it may concern:

Be it known that I, CHARLES C. MEURISSE, citizen of the United States, residing at Chicago, Illinois, have invented certain new and useful Improvements in a Polo Mallet; and I do hereby declare the following to be a full, clear, and exact description of the invention, such as will enable others skilled in the art to which it appertains to make 10 and use the same.

My invention relates to polo mallets and in some of its general aspects aims to provide effective means for increasing the strength and durability of both the head 15 and the shaft of the mallet, for increasing the resiliency of the mallet head, for suitably limiting the whipping action of the handle, and for improving the general appearance of the mallet.

20 In my copending application No. 570,641 for a patent on a polo mallet, as filed on June 24, 1922, I have disclosed a mallet construction in which the whipping of the shaft is limited by constructing this shaft 25 of a relatively flexible main portion (such as a cane or rattan) spliced to an inflexible handle portion of hickory or the like. I have also shown means for reinforcing the shaft adjacent to the mallet head, while 30 both of the features as thus disclosed have proven highly advantageous, I have found that the severe shocks to which the mallet is subjected in use will sometimes overstrain the spliced joint. I have also found that 35 while the said reinforcing of the lower end of the shank strengthens the shaft at its weakest point, the likelihood of splitting the head of the mallet remains as before.

To overcome these drawbacks, my present 40 invention aims to provide simple and effective means for reinforcing the upper portion of the shaft, and desirably aims to employ means for this purpose which can be used equally well either for reinforcing the jointed portion of a two-piece shaft constructed after the manner of my said copending patent application for affording the entire flexure-limiting effect when employed with a single piece shaft. It also 45 aims to provide a reinforcing for the mallet head which will prevent a splitting of the latter, which will afford added resiliency for the head so as to permit the use of softer and lighter woods for the main portion of 50 the head when so desired, and which will

add decidedly to the appearance of the mallet as a whole. Still further and also more detailed objects will appear from the following specification and from the accompanying drawings, in which—
60

Fig. 1 is a perspective view of a polo mallet embodying my invention.

Fig. 2 is an enlarged and partly sectioned elevation of the upper portion of the shaft of the mallet of Fig. 1 before the usual wrapped handle is affixed to the same, showing a two-piece shaft construction.
65

Fig. 3 is a similarly enlarged view of a corresponding portion of a single piece shaft.
70

Fig. 4 is an enlarged central and longitudinal section through the head of the mallet and the adjacent portion of the mallet shaft.

Figs. 5, 6 and 7 are reduced sectional views showing certain steps in the shaping of the sheathing for the mallet head.
75

Referring first to my novel shaft construction, I accomplish the desired reinforcing of the shaft by tightly encasing both the 80 handle portion of the shaft and the adjacent portion of the shaft for some distance below the handle proper, with a tubular sheath. For this purpose, I desirably employ a tube having some resiliency and pref- 85 erably use a material which is adapted to be forced tightly upon the shaft portions housed by the same, such as one of the so-called "pyroxylin plastics" which are com- 90 monly marketed under the trade names of celluloid, pyralin, and the like. While tubing made of such material has considerable resiliency and elasticity, such tubing also can be made fairly plastic by heating the same to a temperature which slightly ex- 95 ceeds the boiling point of water and which will not affect either the materials of which a polo mallet shaft is ordinarily made or the spliced joint in a two-piece mallet shaft.
100

For example, Figs. 1 and 2 show a mallet shaft comprising a main portion 1 of a rattan of the order of a tapered cane, this being jointed to an upper hickory portion 1 by a bevel splice and the splice being reinforced by wooden pins 3 extending trans- 105 versely of the shaft. After the two-piece shaft proper has been thus constructed, I slip its upper end into a tube 4 of pyralin, celluloid or the like, which tube has previously been somewhat softened by immersing 110

the same for a short period of time in steaming hot water. This tube is desirably of such a length as to house the normal handle portion and to extend downward along the shaft beyond the said splice. While the tube is still in its softened or semi-plastic condition, I subject it to the contracting action of a die forced over the same, such as the one shown somewhat diagrammatically in dotted lines at 5 in Fig. 2, thereby forcibly contracting the tube so that it will tightly house the shaft portions encased by it. As soon as the die has thus been passed over the tube, I cool the tube (as for example by subjecting it to cold water), thereby hardening the tube in its contracted form. Then the wrapped and built up handle proper can readily be affixed in the usual manner, as shown for example at 6 in Fig. 1.

With the upper portion of the mallet shaft thus encased, it will be obvious from Figs. 1 and 2 that the tube 4 reinforces the spliced joint so as to prevent an overstraining of the latter, and also that this reinforcing tube assists in limiting the upward extent of the whipping action to which the shaft is subjected when the mallet is in use. Moreover, since the encasing tube or sheath is in itself made of a resilient and somewhat flexible material, the whipping action of the shaft does not stop sharply at the lower end of this tube but is continued to a more limited extent for a slight distance above this lower end, thereby preventing any tendency towards snapping off the shaft opposite the lower end of the tube.

The same effect of limiting the whipping of the shaft to a substantially predetermined proportion of the shaft is similarly attained with a single-piece shaft construction, such as that shown in Fig. 3 where the pyralin or celluloid tube 4 has been tightly forced upon a cane shank 7. In practice, I have found such a single-piece shank construction to be quite satisfactory when the cane is of a short jointed variety, but for a long jointed cane, I preferably employ a two-piece shaft construction such as that of Fig. 1.

To improve the mallet head construction, I also employ a similar material as the casing for the wooden head, as for example after the manner shown in Fig. 4. In this case, the head consists of a core 8 of any suitable wood, which core desirably is turned to the usual elongated barrel shape so as to have each end smaller in diameter than the middle of the head, this core being tightly inclosed by a sheath 9 of pyralin, celluloid or the like. To affix the sheath for this purpose, I may start with a cylindrical tube of a bore corresponding substantially to the diameter of either end of the wooden core 8, as shown in Fig. 5. After softening this tube somewhat by means of hot water,

I force it upon a mandrel so as to expand its upper portion to a taper corresponding to that of one longitudinal half of the wooden core, while also expanding the other half of the tube to a cylinder corresponding approximately in bore to the largest diameter of the wooden core. Having thus stretched the original cylindrical tube into one substantially as shown in Fig. 6, I suitably resoften this tube, slip the wooden core into the same and then contract the entire tube or sheath about the wooden core by forcing counterpart dies 10 over the same as shown in Fig. 7, after which the sheath is hardened by means of cold water.

With the mallet head sheathed in this manner, it will be obvious that the casing will prevent a cracking or a splitting of the core or head proper, thereby greatly increasing the effective life of the mallet. Furthermore, the resiliency of such a casing or sheathing is highly desirable in a head of this kind and in view of it I can employ a lighter and softer wood for the core of the head if I so desire. By so doing I can attain the highly desirable object of lightening the mallet as a whole, which makes a manipulation of the same less tiring to the user. After the core or head proper has been thus encased, I bore it transversely and affix the shaft in the usual manner, as for example by means of a wedge 11. I may also apply a metal protecting shield 12 to the adjacent portion of the shaft after the manner described in my said copending patent application #570641, and in any event I desirably wrap this lower shaft portion with twine 13 in the usual manner. Incidentally, the material thus employed as the sheathing for the mallet head and for a portion of the shaft can be varied in color as desired, since such materials are readily obtainable in a variety of colors. I am therefore able to suit varying tastes of the users, and also can provide mallet portions of strikingly different colors as an aid to identifying the different teams without loading the wood of the mallet head with any paints or the like which might affect its durability.

However, while I have illustrated and described my invention as employed with mallet shafts of certain materials and as having the protective sheathing affixed by certain operations, I do not wish to be limited to the methods of manufacture thus described, nor to the various details of construction and arrangement here disclosed, it being obvious that the same might be modified in many ways without departing either from the spirit of my invention or from the appended claims.

I claim as my invention:—

1. A polo mallet shaft comprising a shaft having the lower and major portion thereof

resilient and having an upper relatively inflexible portion and a stiffening tube housing the entire said inflexible portion and the adjacent upper portion of the resilient portion to limit the whipping action of the shaft when in use, the said tube being tightly contracted about the portion of the shaft housed thereby.

2. A shaft for a polo mallet comprising a resilient lower portion, a substantially inflexible upper portion fastened thereto, and a stiffening tube of pyroxylin plastic housing the inflexible portion and the adjacent part of the resilient shaft portion, the said tube being tightly contracted about the parts housed thereby, and a wrapping over

the upper end of the said tube for affording a handle for the shaft.

3. A shaft for a polo mallet comprising a lower resilient portion and an upper substantially inflexible portion spliced thereto, and a tube of pyroxylin plastic tightly housing the joint between the said shaft portions.

4. A shaft for a polo mallet comprising a lower resilient portion and an upper substantially inflexible handle portion spliced thereto, and a tube tightly housing the said handle portion and extending downwardly of the shaft beyond the said splice.

Signed at Chicago, Illinois, August 11th, 1922.

CHARLES C. MEURISSE.
